UNITED STATES PATENT OFFICE.

FREDERICK TIBBLE, OF GRAND RAPIDS, MICHIGAN.

WATER HYDRANT.

Application filed June 11, 1923. Serial No. 644,593.

To all whom it may concern:

Be it known that I, FREDERICK TIBBLE, a citizen of the United States, residing at Grand Rapids, in the county of Kent and 5 State of Michigan, have invented certain new and useful Improvements in Water Hydrants, of which the following is a specification.

My invention relates to improvements in 10 hydrant valves and its object is to provide a means whereby a hydrant will automatically drain itself as soon as the water supply is shut off, and will automatically close the drain pipe when the supply is passing 15 through the hydrant.

I attain this object by the mechanism and arrangement of parts shown in the accompanying drawing, in which Fig. 1 is a vertical section of the hydrant on the line 1—1 20 of Fig. 2 and of the actuating nut on the line 1—1 of Fig. 4, the stem or neck of the hydrant being left in its normal form. Fig. 2 is a bottom plan of the hydrant showing the positions of my several chambers covering 25 the valve openings and seats. Fig. 3 shows the cap removed from the hydrant, on the line 3—3 of Fig. 1 to more plainly show the valve actuating mechanism, and Fig. 4 is a plan of the actuating nut common 30 upon all hydrants.

Similar reference characters indicate similar parts throughout the several views. In the drawing 1 is the hydrant body, 2 is the hydrant cap, 3 is the hydrant neck, 35 4 is the actuating nut, and 5 is the actuating rod by means of which the hydrant valve 15 is usually operated. In my device I have placed two valves, namely, the flushing or service valve 15 and a drain valve 9. To 40 make this arrangement operative it is necessary to place these valves upon opposite sides of the valve seats, as follows: the valve 15, being the service valve, is placed below the partition 19, and for this purpose I pro-

45 vide a receiving chamber 16 having an opening 17 by means of which the said chamber may be connected with the water main, not here shown, while the valve 9 is placed above the partition 19, within the hydrant body 1, 50 so that when the valves are in their normal positions to shut off the water main and drain the hydrant, the service valve is drawn firmly against its seat 15, thus preventing any water to pass this valve and enter the 55 hydrant body, and the valve 9 is raised off of its seat 10 leaving a free opening through

the connecting cylinder 11 into the drain pipe 18, and thence to any available distribution service, as a sewer.

To render the actuating rod 5 available for use with this distribution of valves it is necessary to provide a cross girt or yoke 6 so disposed that it may be firmly connected with the actuating rod 5 and with both of the valve rods, 7 and 12, which are made to slide freely through the guide bodies 8 which are mounted upon the arms 13 in such a manner as to leave an absolutely free passage for the flow of water into, and out of the hydrant. Thus, it will be understood, when the actuating nut 4 is revolved to force the valves downwardly the service valve will be opened for the free entrance of water into the hydrant and the drain valve 9 is closed so there is no possibility of a waste of water through this valve opening, and when the nut is made to revolve to close the service valve the drain valve is raised from its seat and the valve opening is free for the escape of water from the hydrant sufficiently fast to avert all danger of the water freezing in the hydrant, no matter what the temperature may be when the hydrant is in use.

My receiving and discharge appliance is made separate from the hydrant and is so arranged that it may be readily connected with any stock hydrant, as by the use of bolts *d*. *a*, *b* and *c* represent respectively the ordinary connecting flanges upon the body and cap of a hydrant, and the bolts by means of which these flanges are secured together, and the heavy black line between these flanges represents packing, as ordinarily used, and at *e* I have shown the positions of the ordinary discharge openings or hose coupling lugs on the hydrant.

Having thus fully described my invention, what I claim as new, and desire to secure by Letters Patent, is:

In a water hydrant, an enclosed water chamber consisting of a cup shaped lower part having its bottom plate integral therewith and provided with valve openings therethrough, and a dome shaped cap having a longitudinally apertured, upwardly extending neck integral therewith, a nut mounted upon said neck and having an opening therethrough, the water chamber having openings therethrough for the passage of water therefrom, an outflow valve seated upon the upper side of the bottom

plate, and an inflow valve seated upon the lower side of the bottom plate, a valve rod extending upwardly from each valve, a cross bar within the water chamber securely connected with the upper ends of said valve rods, an actuating rod connected with said bar at the longitudinal center thereof and extending upwardly through the aperture in the neck and nut, a screw thread upon

5 said rod made to mesh with a corresponding screw thread in the nut for open-

ing and closing the valves by the action of the nut thereon, a detachable chamber bolted to the bottom plate and adapted to be connected with a water main, and a sleeve integrally connected therewith and adapted to permit a full free flow of water from the hydrant into a sewer connection. 15

Signed at Grand Rapids, Michigan, June 8, 1923.

FREDERICK TIBBLE.
